GILLING MACHINE AND DRAWING MACHINE
FOR THE TREATMENT OF FIBROUS MATERIAL

John Hughes, Rochdale, England

Original application July 28, 1934, Serial No. 737,368. Divided and this application May 7, 1936, Serial No. 78,322. In Great Britain July 29, 1933

4 Claims. (Cl. 19—158)

This invention relates to gilling machines, worsted draw frames and like machines for preparing fibrous material for spinning or other treatment or use, as set forth in the specification 5 of my co-pending application Serial No. 737,368 filed July 28, 1934, of which the present application is a division.

More particularly, the invention relates to mechanism for reciprocating a slide or bar to 10 carry, or to transmit reciprocating motion to, a surface roller or rollers or other device or devices for use in winding fibrous material in the form of slivers or the like into balls or rolls.

The invention provides an assembly adapted to 15 be fitted to a gilling machine, worsted draw frame or like machine, comprising a plate which when in position is disposed vertically and which carries a slide-bar-actuating crank and gearing for transmitting motion to the crank.

20 The said plate and parts provided in or upon it can be easily machined and erected or applied for use, are neat and compact in disposition, and can be used if need be for either end, right-hand or left-hand, of a machine.

25 Other objects and features of the invention are set forth in the following description.

In the accompanying drawing, Fig. 1 is a front elevation showing mechanism comprising a crank for reciprocating the slide or bar carrying surface 30 rollers in a gill box or worsted draw frame or analogous machine. Fig. 2 is mainly a side elevation of parts shown in Fig. 1 and in part a vertical section taken on the plane indicated by the line II—II of Fig. 1. Fig. 3 is mainly a plan 35 and partly a section taken on the plane indicated by the line III—III of Fig. 1. Fig. 3 also shows in horizontal section parts broken off in Figs. 1 and 2.

The same characters of reference indicate corresponding parts in the several views.

Referring to the drawing, the slide or bar 111 to be reciprocated is provided or formed with a depending plate 112 having arms 113, 114 forming between them a slide-way 115 rigid with the 45 slide and disposed transverse to the direction of reciprocation of the slide 111. 116 denotes a radially adjustable crank-pin carried on a crank-plate 117 and caused, by means of a slide-block 118 mounted upon it, to engage the slide-way 115. 50 The crank-plate 117 is mounted to be revoluble relatively to a vertical plate 119 secured to or formed upon a stationary part 120 of the machine and serving also to carry gearing comprising eccentric toothed wheels 121, 122 for revolving the 55 crank-plate. The gearing for transmitting mo-

tion to the crank 116 comprises, in addition to the eccentric toothed wheels 121, 122, a worm wheel 123 which receives motion from a worm 124 on a driving shaft 125 and which is in connection with a gear wheel 126, which, by means of an intermediate wheel 127 transmits motion to a toothed wheel 128 in connection with the eccentric wheel 121, a toothed wheel 129 in connection with the crank plate 117, and a toothed wheel 130 which is in connection with the other 10 eccentric wheel 122 and which transmits motion to the toothed wheel 129. The toothed wheel 129 has a pitch circle of a diameter twice that of the toothed wheel 130 in mesh with it, so that the speed of the crank 116 is increased and decreased 15 twice in each revolution. The wheels are so proportioned and disposed that the crank 116 is revolved and the slide or bar 111 reciprocated with the frequency requisite, and that the crank 116 is revolved with the greatest speed at or 20 near the reversals of the direction of motion of the slide or bar 111, and so that the slide or bar 111 receives an approximately uniform motion in each direction and that the motion is reversed in direction quickly at the end of each stroke. The 25 slide or bar 111 carries surface rollers 131, which revolve in bearing brackets 132 while being reciprocated by means of the slide or bar 111. One surface roller 131 is shown in full and a second is shown in part. In Fig. 3 parts between 30 the ends of the one surface roller 131, of which the two ends are shown, the slide or bar 111 and the part of the plate 112 from which the arms 113, 114 extend are broken away for parts below them to be shown, the arms 113, 114 being shown 35 in horizontal section taken approximately on the plane indicated by the arrow 133 in Fig. 1.

In the preferred construction illustrated the plate 119 is so formed that holes or slots therein are disposed symmetrically about a plane transverse to the direction of movement of the slide or bar 111, so that parts to be applied or attached at the opposite sides of that plane may be applied or attached at one side or the other as may be requisite or convenient. Preferably the crank 45 116 is formed as a pin adapted to be inserted from the front of the machine or other place easy of access into the crank plate 117, whereby adjustment is facilitated.

The plate 119, which is upright in use, is 50 formed at the upper part with ears 134, 135 for attachment to the stationary part 120 of the machine and is formed in the middle of its width with a horizontal slot 136 and a vertical slot 137, one above the other, in which are adjustable and 55

secured, by nuts, studs 138, 139 carrying the eccentric toothed wheels 121, 122, respectively, in mesh with one another and fast, respectively, with the toothed wheels 128, 130. Two elongated holes 140, 141 are formed at opposite sides of and equidistant or approximately equidistant from the vertical slot 137 and with central parts at a level slightly below its center, one hole 140 to allow passage of part of a bracket 142 forming a bearing for a stud 143 to carry the crank plate 117 and the toothed wheel 129, and the other hole 141 to allow passage of part of a bracket 144 to carry a shaft 145 to carry the worm wheel 123 and toothed wheel 126. Above and below the oval holes 140, 141 are formed vertical slots 146 for the passage of bolts for securing in position the brackets 142, 144, which are themselves formed with horizontal slots 147, 148, respectively, for the passage of said bolts. At opposite sides of and equidistant or approximately equidistant from the horizontal slot 136 are formed curved slots 149 approximately concentric with the stud 138, and in one of these curved slots 149 a stud 150 which bears the wheel 127 is secured by a nut, while the other curved slot 149 is vacant. The bracket 144 is bolted in such a position on the plate 119 that the worm wheel 123 meshes with the worm 124. The wheel 127 on the stud 150 is in mesh with the toothed wheel 129. The toothed wheel 129 is secured upon a sleeve or boss formed on the crank plate 117, and the crank plate 117 and the toothed wheel 129 are held upon the stud 143 by means of a collar 151 and a set-screw 152, the set-screw 152 and stud 143 being formed with passages, not shown, by which lubricant may be led to a central hole in the crank plate 117. The crank plate 117 is formed with a radial slot 153 in which the crank pin 116 is adjustable and secured in position. The slide-block 118 applied to the crank is adapted to slide up and down in the slide-way formed by the arms 113, 114. With the arrangement of the toothed wheels 126, 128 in connection with the worm wheel 123 and the lower eccentric toothed wheel 121, any requisite frequency of reciprocation of the plate or bar 111 may be obtained, and by use of suitable eccentric wheels 121, 122 any requisite relation between the maximum and minimum speed of the crank plate 117 may be obtained.

What I claim is:—

1. In a gilling machine, worsted draw-frame or like machine, mechanism for the purpose hereinbefore set forth, comprising a stationary vertical plate formed in the middle of its width with a horizontal slot and a vertical slot one above the other, said plate also formed with two elongated holes at opposite sides of and approximately equidistant from said vertical slot with their centers at a level slightly below the center of said vertical slot, vertical slots above and below said holes, and two curved slots at opposite sides of and approximately equidistant from said horizontal slot, studs secured in the vertical and horizontal slots in the middle of the plate, eccentric toothed wheels mounted on said studs and in gear with one another, toothed wheels fast with said eccentric toothed wheels, a bracket with horizontal slots secured in the vertical slot above and below one of said elongated holes and

extending into said elongated hole, a stud in said bracket, a crank-plate on said stud, a crank radially adjustable in said crank-plate, a toothed wheel in connection with said crank-plate and in mesh with the toothed wheel fast with the eccentric toothed wheel on the stud in the first-mentioned vertical slot, a gear wheel in mesh with the toothed wheel fast with the other eccentric toothed wheel, a stud secured in one of said curved slots and carrying said gear wheel, a toothed wheel in mesh with said gear wheel, a shaft to carry said last-mentioned toothed wheel, a driving member on said shaft, a bracket which carries said shaft and is formed with horizontal slots and is secured in the vertical slots above and below the other elongated hole and extends through said other elongated hole, means for driving said driving member, a slide-block on said crank, and a plate presenting a slide-way receiving said slide-block and given reciprocatory movements in the rotation of said crank.

2. In a gilling machine, worsted draw-frame or like machine, in combination with a reciprocating slide to effect reciprocating motion of means for use in winding fibrous material into balls or rolls, a vertical slide-way rigid with said slide and disposed wholly below said slide, a crank in engagement with said slide-way, a crank-plate carrying said crank, a stationary vertical plate on which said crank-plate is revolvably mounted so as to be vertically and horizontally adjustable, and gearing all carried by said stationary vertical plate and serving to transmit rotary movement to said crank-plate, said gearing including intermeshing eccentric toothed wheels, toothed wheels in connection with said eccentric toothed wheels, a driving gear wheel, a toothed wheel in engagement with said gear wheel serving to drive one of the toothed wheels in connection with said eccentric toothed wheels, and a toothed wheel in connection with said crank-plate and in mesh with the toothed wheel in connection with the other of said eccentric toothed wheels, said vertical plate being formed in the middle of its width with a horizontal slot and a vertical slot one above the other and with curved slots equidistant from said horizontal slot, studs carrying said eccentric toothed wheels and secured in said horizontal and vertical slots, and a stud carrying the toothed wheel in engagement with said gear wheel and secured in one of said curved slots.

3. In a gilling machine, worsted draw-frame or like machine, in combination with a reciprocating slide for transmitting reciprocating motion to parts for winding fibrous material into balls or rolls, a vertical slide-way rigid with said slide and disposed wholly below said slide, a radially adjustable crank contrived to work in said slide-way, a crank plate carrying said crank, and gearing including intermeshing eccentric toothed wheels for rotating said crank plate, and driving and intermediate gear wheels for rotating said eccentric toothed wheels, bearing parts for said crank plate and said wheels, a vertical plate carrying all said bearing parts, said vertical plate formed in the middle of its width with a horizontal slot and a vertical slot, studs secured in said slots and carrying said eccentric toothed wheels, a stud carrying said crank plate, and a bracket forming a bearing for said last mentioned stud and mounted for adjustment on said vertical plate, said vertical plate formed with a curved slot, and a stud carrying said intermediate gear wheel and adjustable in said slot.

4. In a gilling machine, worsted draw-frame or like machine, in combination with a reciprocatory slide to effect reciprocatory motion of means for use in winding fibrous material into balls or rolls, 5 a vertical slide-way rigid with said slide and disposed wholly below said slide, a crank in engagement with said slide-way, a crank-plate carrying said crank, a stationary vertical plate on which said crank-plate is revolubly mounted so as 10 to be vertically and horizontally adjustable, and gearing all carried by said stationary plate and serving to transmit movement to said crank-plate, said gearing including intermeshing eccentric toothed wheels, toothed wheels in connection 15 with said eccentric toothed wheels, a vertically and horizontally adjustable driving gear wheel, a toothed wheel in engagement with said gear wheel serving to drive one of the toothed wheels in connection with said eccentric toothed wheels, and a toothed wheel in connection with said crank-plate, said last-mentioned toothed wheel meshing with the toothed wheel in connection 5 with the other of said eccentric toothed wheels and being made with a pitch circle twice that of the toothed wheel in mesh with it, said vertical plate being formed in the middle of its width with a horizontal slot and a vertical slot 10 one above the other and with curved slots equidistant from said horizontal slot, studs carrying said eccentric toothed wheels and secured in said horizontal and vertical slots, and a stud carrying the toothed wheel in engagement with said gear 15 wheel and secured in one of said curved slots.

JOHN HUGHES.
